(57) **CLAIM**

The ornamental design for a shoe lace pull hook, as shown and described.

DESCRIPTION

FIG. 1 is a front perspective view of the shoe lace pull hook showing a spherical manual grab handle with an extension that terminates in an open hook;

FIG. 2 is an upper perspective view of the shoe lace pull hook showing the spherical manual grab handle with the extension that terminates in the open hook;

FIG. 3 is a hook end perspective view of the shoe lace pull hook showing the spherical manual grab handle with the extension that terminates in the open hook;

FIG. 4 is a spherical manual grab handle end perspective view of the shoe lace pull hook showing the spherical manual grab handle with the extension that terminates in the open hook;

FIG. 5 is an in use upper perspective view of the shoe lace pull hook showing the spherical manual grab handle being grasped by a user's hand in a partially encompassing manner partially covering the grab handle with the user's hand with the open hook being inserted into a shoe lace to be able to manually pull upward on the shoe lace pull hook to tighten a portion of the shoe lace, the broken line showings of the shoe and the hand are provided for the purpose of environment and form no part of the claimed design;

FIG. 6 shows a top plan view of the shoe lace pull hook showing the spherical manual grab handle with the extension that terminates in the open hook;

FIG. 7 shows a bottom footprint view of the shoe lace pull hook showing the spherical manual grab handle with the extension;

FIG. 8 shows an end elevation view of the shoe lace pull hook showing the spherical manual grab handle with the extension;

FIG. 9 shows an opposing end elevation view of the shoe lace pull hook showing the spherical manual grab handle with the extension that terminates in the open hook; and, FIG. 10 shows a side elevation view of the shoe lace pull hook showing the spherical manual grab handle with the extension that terminates in the open hook.
